CLAIM

The ornamental design for a balance training device, substantially as shown and described.

DESCRIPTION

FIG. 1 is a top perspective view of a balance training device according to an embodiment of the design.

FIG. 2 is a bottom perspective view of the balance training device shown in FIG. 1.

FIG. 3 is a first side view of the balance training device shown in FIG. 1 (a second side view of the balance training device being an identical mirror image thereof).

FIG. 4 is a first end view of the balance training device shown in FIG. 1 (a second end view of the balance training device being an identical mirror image thereof).

FIG. 5 is a top view of the balance training device shown in FIG. 1.

FIG. 6 is a bottom view of the balance training device shown in FIG. 1.

FIG. 7 is a detailed view of a portion of the balance training device shown in FIG. 6.

FIG. 8 is a cross sectional view of the balance training device shown in FIG. 2 taken along line 8-8.

FIG. 9 is a cross sectional view of the balance training device shown in FIG. 2 taken along line 9-9.

FIG. 10 is a top perspective view of a balance training device according to another embodiment of the design.

FIG. 11 is a bottom perspective view of the balance training device shown in FIG. 10.

FIG. 12 is a first side view of the balance training device shown in FIG. 10 (a second side view of the balance training device being an identical mirror image thereof).

FIG. 13 is a first end view of the balance training device shown in FIG. 10 (a second end view of the balance training device being an identical mirror image thereof).

FIG. 14 is a top view of the balance training device shown in FIG. 10; and,

FIG. 15 is a bottom view of the balance training device shown in FIG. 10.

The broken line portions of the figure drawings are included to show portions of the article that form no part of the claimed design.
